CLAIM

We claim the ornamental design for a container holder, as shown and described.

DESCRIPTION

FIG. 1 is a top, front, and left side perspective view of a container holder showing our new design;

FIG. 2 is a right side elevational view thereof;

FIG. 3 is a top plan view thereof;

FIG. 4 is a front elevational view thereof;

FIG. 5 is a rear elevational view thereof; and,

FIG. 6 is a bottom plan view thereof.

FIG. 6

UNITED STATES PATENT AND TRADEMARK OFFICE
CERTIFICATE OF CORRECTION

PATENT NO : D418,708

DATED : January 11, 2000

INVENTOR(S) : Joseph S. Kanfer et al.

It is certified that error appears in the above-identified patent and that said Letters Patent
are hereby corrected as shown below:
In the Drawing:

Fig. 2 should read "Fig. 2 is a right side elevational view thereof, the
left side being a mirror image of that shown;"

Signed and Sealed this

Fifteenth Day of May, 2001

Attest:

NICHOLAS P. GODICI
